WELL POINT CONSTRUCTION

Barnett Share, Jamaica Estates, N. Y.

Application January 31, 1952, Serial No. 269,245

4 Claims. (Cl. 166—5)

1

This invention relates to soil drainage apparatus or devices of the type known as well points, and more particularly to improvements in well points of the type disclosed in my U. S. Patent No. 1,915,136.

Well points of the type to which the present invention is directed serve the dual functions of jetting the soil by water pressure to prepare a hole into which the well point is inserted to the desired depth, and of draining the water entering the hole, by suction, to de-water the adjacent soil prior to excavation. By use of the proper number of well points, properly arranged and operated, a pre-selected area may have the soil excavated therefrom to the desired depth under dry excavating conditions.

To these ends, the well points include a lower jetting head connected to an upper suction head by a pressure and suction line including an internally disposed pipe having longitudinally extending ribs or flutes. A water pervious member in the form of a cylindrical screen embraces the pipe ribs or flutes and is surrounded, for protective purposes, by a perforated metal cylinder.

In operation, a source of water under pressure is connected to the suction head, valves being provided to direct the water through the interior of the pipe to the jet head. Water under pressure, discharged from the jet head, forces the soil away from the jet head boring a hole into which the well point then advances.

When the well point is at the desired depth, the water jetting is terminated and a suction line is connected to the suction head. The valves are now so arranged as to block communication between the suction line and the jet head. Water flows through the perforated metal cylinder and the screen perforations into the longitudinal channels formed by the flutes or ribs, and downwardly into a chamber at the lower end of the suction line. The water is then drawn up through the pipe into the suction head and out through the suction line.

With present devices, any increase in the excavating action of the water jetting must be obtained by increasing the water pressure or by reducing the diameter of the well point and thus of the excavation. These expedients either require a higher capacity pump, for the greater pressure, or reduce the water draining capacity of the well point due to the reduced diameter.

In accordance with the present invention, greater excavating capacity is provided by im-

2

parting a turbulent or swirling action to the jetted water. This action is effective in forcing the soil to the periphery of the excavation, whereas merely increasing the water pressure tends to compact the soil in alignment with the point and is of no practical effect in displacing the soil laterally out of the way of the point. This lateral displacement of the soil is what ultimately makes room for the advance of the well point into the excavation.

During drainage of the water by flowing through the perforated sleeve and screen, soil is carried against the outer surface of the screen tending to at least partially block the screen openings. This necessitates frequent withdrawal of the well point and disassembly for cleaning the screen.

In the invention arrangement, the interior pipe is formed with a series of peripherally spaced openings just above from the connection to the jet head. By supplying water under pressure to the well point, as in jetting a hole in the soil, some of the water discharges through these openings against the screen, tending to spread over the latter and wash away the soil accumulations. This water also assists the excavating action to some extent by removing soil from the excavation around the well point.

For an understanding of the invention principles, reference is made to the following description of typical embodiments thereof as illustrated in the accompanying drawing. In the drawing:

Fig. 1 is an elevation of a structure incorporating the invention;

Fig. 2 is a section taken on the line 2—2 of Fig. 1;

Fig. 3 is an enlarged section of the jetting head of the well point shown in Fig. 1;

Fig. 4 is a section taken on the line 4—4 of Fig. 3; and

Fig. 5 is a fragmentary view similar to Fig. 1, illustrating a modification.

Referring to the embodiment of the invention shown in Figs. 1 to 4, Fig. 1 illustrates a section 10 of a well point generally similar to that disclosed in my aforementioned U. S. Patent No. 1,915,136, those portions of the well point not directly pertinent to the instant invention and not necessary to an understanding thereof having been omitted to simplify and clarify the disclosure. Well point section 10 includes an intermediate pressure or suction line generally indicated at 15 and secured at its upper end in to a suction head 11 threaded for connection

to a suitable water line for supplying water under pressure to the well point or withdrawing water draining into the well point.

The pressure or suction line 15 includes an internally disposed pipe 12 which is threaded or otherwise secured at its upper end into head 11. The pipe 12 is formed with longitudinally extending flutings 13 the lower ends of which are externally threaded for connection into a jetting head generally indicated at 14. The outwardly facing grooves between adjacent flutings form water channels 16.

A relatively fine cylindrical screen 17 embraces pipe 12, contacting the flutings 13 and extending between heads 12 and 14. A relatively heavy water pervious cylinder or coarse screen 18 surrounds and overlies screen 17, likewise extending between heads 12 and 14.

Jetting head 14 is generally cylindrical and its lower edge is serrated to facilitate excavating, as best seen in Figs. 1 and 3, having circumferentially spaced teeth 21 shown as six in number by way of example only. Midway of its length, head 14 has a partition 22 with a central aperture 23 forming a seat for a ball valve 20. Ball 20 blocks aperture 23 when the well point is connected to a suction line, moving upwardly to engage partition 22. A cross wire or pin 24 limits downward movement of ball 20 away from diaphragm 22. Partition 22 divides head 14 into an upper chamber 26 and a nozzle section 27.

During an excavating operation, water under pressure supplied to head 11 passes downwardly through the interior of pipe 11, forcing ball 20 away from seat 23 and discharging from nozzle section 27 of jetting head 14. The water displaces soil from beneath head 14, eventually moving the displaced soil laterally so that the well point can be moved into the excavated hole.

When the well point is at the desired depth, the water pressure line is disconnected from head 11 and a suction line is connected to this head. The suction causes ball 20 to move up and close aperture 23. Water flows inwardly through the perforations of member 18 and through screen 17 into the channels 16. The water flows down channels 16 to chamber 26 and then upwardly through the interior of pipe 12 and out through suction head 11.

As set forth above, any attempt to increase the excavating action by an increase in the water pressure not only requires greater pump capacity but also at least partially defeats its own purpose by a more forceful compacting action on the soil directly beneath the jetting head without any corresponding increase in the rate of lateral displacement of the soil. Thus, the increase in excavating rate is nowhere near proportional to the requisite increase in power requirements.

In accordance with the present invention, an increase in the rate of lateral displacement of the soil, and thus in the excavation rate is effected by imparting a swirl to the water jet and without an increase in the water pressure. In the arrangement shown in the drawings, and more particularly in Figs. 3 and 4, such swirl is effected by providing helically extending ribs or vanes 25 on the interior surface of nozzle section 27 of jetting head 14. These vanes extend from partition 22 to the outer edges of teeth 21 and, in the arrangement shown, are equal in number to the teeth. However, a larger or smaller number of vanes may also be used, the illustrated number being exemplary only.

Vanес 25 act like the stator vanes of a turbine,

imparting an angular velocity to the jetting water and forcing it laterally with considerable force. This greatly increases the rate of lateral displacement of the soil and thus the rate of excavation. With the greater turbulence of the water, a larger hole is formed than would be possible with a smooth jet under an equal pressure.

It will be noted that the vanes 25, while increasing the effectiveness of the excavating action of the well point, in no way impair the draining efficiency of the device. This is true because the ball 20 seals the aperture 23 during drainage, thus completely removing the jetting head 14 from the hydraulic circuit. The drainage is effected solely through the channels 16 and the vanes 25 in no way interfere with this operation.

In certain cases it will be desirable to increase the turbulence of the pressurized water emerging from the jetting head 14, even at the expense of somewhat slowing down the drainage operations. A modified structure suitable for this purpose is shown in Fig. 5 which shows a pipe 112 surrounded by screens 117 and 118. The vanes 113, equivalent in function to flutings 13, are helically extended along pipe 112. Alternatively, these may be helical flutings of pipe 112. Thus, the channels 116 are helical and impart an angular velocity to the jetting water. The construction of Fig. 5 may be used with a smooth jetting head or with the jetting head of Figs. 3 and 4.

To clean the screens of accumulated soil without the necessity of withdrawing the well point, pipe 12 is formed with a series of small apertures 30 immediately above jetting head 14 and at the bases of channels 16. These apertures may be, for example, only $\frac{3}{8}$ " in diameter. During jetting action, some of the water is discharged under pressure through apertures 30 and against the screens. The water washes soil from the screens and also assists in soil displacement around the well point. Pipe 111 (Fig. 5) may have similar apertures 130.

While specific embodiments of the invention have been shown and described in detail to illustrate the application of the invention principles, it should be understood that the invention may be embodied otherwise without departing from such principles.

What is claimed is:

1. In a well point of the type comprising an upper head for connection to a fluid line, a jetting head for discharge of fluid under pressure to remove soil from beneath the well point, a conduit interconnecting said heads and having peripherally spaced longitudinally extending external projections, screen means embracing said conduit and engaging said projections to form with the latter fluid passages external to said conduit, an apertured partition dividing said jetting head into an upper chamber connecting said fluid passages and the interior of said conduit and a lower jetting chamber, and movable valve means controlling flow through the partition aperture, the improvement comprising peripherally spaced helical vanes extending longitudinally of the inner surface of said lower jetting chamber from said partition to the discharge end of said jetting head.

2. In a well point of the type comprising an upper head for connection to a fluid line, a jetting head for discharge of fluid under pressure to remove soil from beneath the well point, a conduit

interconnecting said heads and having peripherally spaced longitudinally extending external projections, screen means embracing said conduit and engaging said projections to form with the latter fluid passages external to said conduit, an apertured partition dividing said jetting head into an upper chamber connecting said fluid passages and the interior of said conduit and a lower jetting chamber, and movable valve means controlling flow through the partition aperture, the improvement comprising peripherally spaced helical vanes extending longitudinally of the inner surface of said lower jetting chamber from said partition to the discharge end of said jetting head, and peripherally spaced cutting teeth on the discharge end of said jetting head, each of said vanes terminating in one of said teeth.

3. In a well point of the type comprising an upper head for connection to a fluid line, a jetting head for discharge of fluid under pressure to remove soil from beneath the well point, a conduit interconnecting said heads and having peripherally spaced longitudinally extending external projections, screen means embracing said conduit and engaging said projections to form with the latter fluid passages external to said conduit, an apertured partition dividing said jetting head into an upper chamber connecting said fluid passages and the interior of said conduit and a lower jetting chamber, and movable valve means controlling flow through the partition aperture, the improvement comprising arranging said projections as helices to impart a swirl to fluid delivered to said jetting head.

4. In a well point of the type comprising an upper head for connection to a fluid line, a jetting head for discharge of fluid under pressure to remove soil from beneath the well point, a conduit interconnecting said heads and having peripherally spaced longitudinally extending external projections, screen means embracing said conduit and engaging said projections to form with the latter fluid passages external to said conduit, an apertured partition dividing said jetting head into an upper chamber connecting said fluid passages and the interior of said conduit and a lower jetting chamber, and movable valve means controlling flow through the partition aperture, the improvement comprising peripherally spaced helical vanes extending longitudinally of the inner surface of said lower jetting chamber from said partition to the discharge end of said jetting head, and arranging said projections as helices to impart a swirl to fluid delivered to said jetting head.
